UNITED STATES PATENT OFFICE.

BENJAMIN F. LAWRENCE, OF BUFFALO, NEW YORK, ASSIGNOR OF ONE-HALF TO
WILLIAM L. GROBE, OF BUFFALO, NEW YORK.

SNOW-PLOW AND BALLAST-SPREADER.

1,125,568.

Specification of Letters Patent. . Patented Jan. 19, 1915.

Application filed October 11, 1912. Serial No. 794,731.

To all whom it may concern:

Be it known that I, BENJAMIN F. LAWRENCE, a citizen of the United States, residing at Buffalo, in the county of Erie and State of New York, have invented new and useful Improvements in Snow-Plows and Ballast-Spreaders, of which the following is a specification.

This invention relates generally to track clearers of the kind commonly known as "snow and ice flangers," and more particularly to an improvement in a device of this character shown and described in Letters Patent of the United States, No. 1,065,453, granted to me June 24, 1913, although the same is not limited to use in this connection. Said patent shows a pair of forwardly-converging plows or blades movable vertically on curved guides and actuated 20 by pneumatic cylinders and pistons, the blades terminating at or near the sides of the railway car on which they are mounted.

It is sometimes desirable in plowing snow to throw the same a greater distance from the track than is possible with blades which terminate at the sides of the car, and also to spread or level ballast to a greater width or distance from the rails than can be accomplished by the use of such blades.

It is the object of my present invention to produce an apparatus having this increased capacity, and the invention consists in providing the car with foldable auxiliary plow and ballast-spreading blades 35 which in their operative or unfolded position form extensions of the main plow-blades and which can be folded or drawn inward to clear switch stands or the sides of bridges and raised to clear railway switches, frogs and crossings in moving the car from place to place.

In the accompanying drawings: Figure 1 is a fragmentary top plan view of a railway car equipped with the improvement. Fig. 2 is a longitudinal section thereof on line 2—2, Fig. 1, the main blades being omitted for clearness. Fig. 3 is a cross section on line 3—3, Fig. 1, showing the auxiliary blades unfolded. Fig. 4 is a cross section on the same line, showing said blades folded. Fig. 5 is a diagrammatic view of

the controlling valve and associated parts. Fig. 6 is an enlarged perspective view of one of the auxiliary blades and its supporting and operating parts, showing the blade 55 completely unfolded. Fig. 7 is a similar view showing the blade partly folded.

Similar characters of reference indicate corresponding parts throughout the several views.

1 indicates the platform of the car which may be of any suitable construction, and which carries the converging main snow and flanger blades or plows 2. These blades are shown by dotted lines in Fig. 1, reference being made to the aforesaid Letters Patent for a full illustration and description thereof.

3, 3 indicate the pneumatic or pressure cylinders by which said blades are respectively actuated, and 4 indicates the compressed air reservoir mounted on the car and with which opposite ends of the pressure cylinders 3 are connected by pipes 5, 6, 7, 8 and 9 through a suitable controlling 70 valve 10 by which the pressure fluid may be alternately admitted to and exhausted from opposite ends of the pressure cylinders 3, to raise or lower the blades.

The particular construction of the parts 80 so far described constitutes no part of the present invention and may be modified, if desired, although such parts are preferably constructed in accordance with the aforesaid Letters Patent.

Arranged at opposite sides of the car are a pair of auxiliary snow plowing and ballast-spreading blades 11 which in their operative position are adapted to form wings or extensions of the main blades 2 and, 90 when not in use, may be swung inwardly under or adjacent to the sides of the car platform to clear switch stands, bridges and other obstructions along the railway in transporting the car. In order to do 95 effective work these auxiliary blades, like the main blades, are vertically movable so that they may be lowered below the heads of the rails when in operation and elevated, when not in use, sufficiently to clear frogs, 100 switches and crossings. To meet these requirements, the auxiliary blades are capable

of a combined vertical and horizontal movement which may be effected by any suitable means but is preferably accomplished by the devices shown in the drawings which are constructed as follows: Each auxiliary blade is hinged or pivoted by means of straps 12 to a vertical post or guide rod 13 rigidly secured to the adjacent outer sill 14 of the car platform and located in such position that when the auxiliary blade is unfolded it stands in line with the companion main blade 2 to form a continuation thereof, as shown in Fig. 1. At its lower end the post 13 is secured to a longitudinal supporting bar or frame 15, the opposite end of which is carried by a rigid hanger 16 depending from the adjacent car sill 14. The two longitudinal bars 15 at opposite sides of the car are firmly braced by tie bars 17. The auxiliary blades are capable of sliding vertically on the posts 13 as well as swinging horizontally thereon.

Coöperating with each auxiliary blade is a vertically swinging member or rock frame 18 arranged lengthwise of the car and preferably of skeleton and approximately triangular form, as shown in the drawings. The inner rod or shaft 19 of this frame is arranged lengthwise on the adjacent supporting bar 15 and journaled in suitable bearings 20 carried thereby. Preferably the rear end of the shaft 19 bears against an abutment 21 which receives the thrust of the triangular rock frame and the unfolded auxiliary blade when in service, thus largely relieving the post 13 from strain. The outwardly extending arm or portion 19¹ of said frame adjacent to the front end of its shaft 19 engages under a lifting lug 22 projecting rearwardly from the auxiliary blade near the post 13, so that upon raising said rock frame the blade is raised, while upon lowering said frame the blade is allowed to descend by gravity to its operative position, as shown in Figs. 2, 3 and 6. The folding and unfolding movements of each blade are effected by the angular outer portion 23 of the rock frame 18 which embraces a guide or bar 24 arranged on the rear side of the blade. This guide is suitably secured to the blade at its upper and lower ends and is separated therefrom by sufficient space to permit the portion 23 of the frame 18 to slide along the guide from end to end thereof. As best shown in Figs. 3 and 6, this guide is gradually curved upwardly and forwardly or toward the post 13. By this construction and arrangement when the rock frames 18 are swung from their horizontal to their upright position they draw the auxiliary blades with them, folding them under the car body, as shown by full lines in Fig.

4, while when said rock frames are lowered to their horizontal position, they push or unfold the auxiliary blades to their operative position. In the last-mentioned position, the diagonal outer bars of the frames 18 form strong and rigid braces for the unfolded blades, the thrust of which is exerted against the abutments 21, relieving the posts 13 from undue strain, as hereinbefore described. The relation of the parts is such that upon raising the rock frames 18, the auxiliary blades are raised on the posts 13 by the initial movement of said frames and are swung inward by the subsequent or continued movement thereof.

To reliably retain the contracted front portion 21 of each frame 18 in engagement with the lug 22, the latter is provided at its free end with a depending pin 25 which engages the adjacent angle of said frame, as best shown in Fig. 6.

Any suitable means may be employed for actuating the rock frames 18, but this is preferably done by compressed air under the control of the same valve 10 which controls the movement of the main blades 2. For this purpose, the rock frames 18 are connected by links 26 with opposite arms of a transverse rock lever 27 pivoted at 28 to a bracket 29 secured to the underside of the car platform. The projecting upper end of this lever is pivoted at 30 to a piston rod 31, the piston of which is fitted in a pneumatic or pressure cylinder 32 arranged transversely underneath the car platform. Compressed air is alternately admitted to opposite ends of the cylinder 32 by branch pipes 33 and 34 of the pipes 7 and 8. The controlling valve 10 is of the four-way type and may be of any appropriate construction. In the example shown in Fig. 5, the pipes 7 and 8 lead to connections 35 and 36 at diametrically opposite sides of the valve case, while the reservoir pipe 9 and an exhaust pipe 37 enter intermediate connections 38 and 39 of the valve case. The valve plug has a pair of ports 40 and 41 so arranged that when the plug is turned to admit pressure to one end of the cylinder 32, the air is allowed to exhaust from the other end thereof. In the instance shown in Fig. 5, the port 41 registers with the pipes 7 and 9, while the port 40 registers with the pipes 8 and 37, supplying pressure to the lower end of the cylinder 32, as viewed in said figure, and exhausting the air at its other end.

In the use of the apparatus, when it is desired to plow snow or spread ballast a greater distance from the track than can be done with the main blades 2, the auxiliary blades 11 are lowered and unfolded by turning the controlling valve 10 to the proper position to admit air to the right hand end

of the cylinder 32, whereupon the lever 27 is swung to the position shown in Fig. 3, thereby first lowering the rock frames 18, withdrawing the portions 21 thereof from 5 the lugs 22 and allowing the blades to descend by gravity, and then unfolding them to the position shown in Figs. 1, 3 and 6.

To withdraw or fold the blades to their inoperative position, the valve 10 is turned 10 to admit air to the opposite end of the cylinder 32, whereupon the rock frames 18 are swung to their upright position, thereby first lifting the auxiliary blades and then swinging them inward as hereinbefore described. In this position, the blades are elevated sufficiently to avoid all obstacles, such as switches, crossings &c. By providing the car with such auxiliary blades or extensions of the main blades, the swath or 15 snow-plowing and ballasting spreading capacity of the apparatus is materially increased, accomplishing a large amount of work in a given time and effecting a great saving in labor and expense.

25 When both the main and the auxiliary blades are arranged to be controlled by the same valve, such as the valve 10, it is desirable to provide means for locking or blocking the piston rod 31 against movement, so that if desired, only the main blades may be lowered and the folded auxiliary blades left undisturbed. This is advantageous where a number of parallel tracks are arranged so closely together that snow 30 or ballast would be thrown upon an adjacent track with the auxiliary blades unfolded. The lock shown in the drawings consists of a vertically-swinging latch 42 pivoted at 43 to the underside of the car track, 35 and adapted to be swung down in front of the outer end of the piston rod, thereby blocking the same and preventing the piston of the cylinder 32 from actuating the rock lever 27, notwithstanding that pressure is 40 supplied to said cylinder at the same time that pressure is supplied to the actuating cylinders 3 of the main blade 2. This latch normally clears the end of said piston rod, as shown by dotted lines in Fig. 2. The 45 latch may be operated from the top of the car platform by a vertically-sliding bar 44 passing through the floor thereof and connected by a bell crank 45 and a link 46 with an arm 47 of the latch. A suitable catch or 50 other retaining means may be used for holding the bar 44 in its upper and lower positions. Such a lock is also desirable even if separate valves be employed for controlling the main and the auxiliary blades, as 55 it prevents the auxiliary blades from unfolding accidentally when the car is backed, avoiding breakage thereof which might otherwise result in case the rear ends of the

blades should catch on the ballast or snow and become unfolded.

I claim as my invention:

1. The combination of a railway car, a plow-blade arranged at the side thereof and pivoted to swing toward and from the car, the blade being movable vertically on its 70 pivot and provided with a lifting-lug, and a rock member arranged to engage said lifting lug and having a sliding connection with the blade to fold and unfold the same.

2. The combination of a railway car, a 75 plow-blade arranged at the side thereof and pivoted to swing toward and from the car, the blade having a guide on its rear side and a vertically swinging actuating member engaging said guide to fold and unfold the 80 blade.

3. The combination of a railway car, a plow-blade arranged at the side thereof and pivoted to swing toward and from the car, the blade being provided on its rear side 85 with an upwardly and forwardly-curved guide bar, and a vertically-swinging actuating member engaging said guide bar.

4. The combination of a railway car, a 90 plow-blade arranged at the side thereof and pivoted to swing toward and from the car, the blade being vertically movable on its pivot and having on its rear side a lifting lug and a guide trending upwardly toward its pivot, and a vertically-swinging rock 95 frame embracing said guide and having a part arranged to engage said lifting lug.

5. The combination of a railway car, a plow-blade arranged at the side thereof and pivoted to swing toward and from the car, 100 an approximately triangular frame pivoted underneath the car to swing vertically, a guide carried by the blade and engaging said frame, and means for operating said frame.

105 6. The combination of a railway car, a plow-blade arranged at the side thereof and pivoted to swing toward and from the car, a vertically-swinging frame pivoted underneath the car and engaging said blade to 110 fold and unfold the same, and an abutment arranged to receive the backward thrust of said frame.

7. The combination of a railway car, foldable plow blades pivoted to swing toward 115 and from opposite sides of the car, vertically-swinging rock-frames pivoted underneath the sides of the car and respectively connected with said blades to fold and unfold them, a transverse lever pivoted intermediate of its ends, links connecting said frames with opposite ends of said lever, and means for actuating said lever.

120 8. The combination of a railway car, a plow-blade vertically movable thereon, a pressure cylinder and piston for operating

said blade, a foldable auxiliary blade arranged at the rear end of the main blade, a pressure cylinder and piston for actuating the auxiliary blade, unitary means for controlling the passage of the pressure fluid to and from both of said cylinders, and means for blocking the outward movement of the piston of that pressure cylinder which oper-

ates the auxiliary blade, to lock the latter in its folded position. 10

Witness my hand this 9th day of October, 1913.
